United States Patent Office

Des. 173,638
Patented Dec. 14, 1954

173,638

JUG OR SIMILAR ARTICLE

Vera C. Bryant, Rock Creek, Ohio

Application April 12, 1954, Serial No. 29,948

Term of patent 14 years

(Cl. D58—25)

FIG. 1

FIG. 2

To all whom it may concern:

Be it known that I, Vera C. Bryant, a citizen of the United States, residing at Rock Creek, in the county of Ashtabula and State of Ohio, have invented a new, original, and ornamental Design for a Jug as Similar Article of which the following is a specification, reference being had to the accompanying drawing, forming a part hereof.

I claim:

The ornamental design for a jug or similar article, substantially as shown.
